UNITED STATES PATENT OFFICE

WILLIAM W. HARRIS, OF BROCKTON, MASSACHUSETTS

ACETYLENE GENERATOR

Application filed October 5, 1929. Serial No. 397,620.

This invention relates to acetylene generators and particularly to the type of generators wherein the carbide feeding mechanism, together with its means of actuation, comprising a spring pressed yieldable gas wall carrying a reciprocating feed plunger operating through a restricted feed opening, is entirely self contained, in other words, wholly incorporated within the generator and thus rendering the apparatus especially adaptable for portable purpose.

An object of the invention is to provide an efficient acetylene generator of simple and economical structure wherein the arrangement of working parts is such as to permit of quick and accurate assembly in ordinary factory practice thereby insuring uniform operating efficiency of the factory product.

A special object of the invention is to provide an acetylene generator having a carbide feeding mechanism highly sensitive to slight changes in gas pressure within the generator and automatically responsive to such slight changes to generate gas only in quantity commensurate to any variation of service requirement, thereby insuring a much desired degree of pressure stability in the service output, the particular formation of the feed plunger part of such carbide feeding mechanism being an important means to this end.

Another object of the invention is to provide an acetylene generator having a manual control part of the carbide feeding mechanism for starting or stopping the generation of gas which is incapable of being either willfully or ignorantly operated to manually force the feeding of carbide beyond the amount deliverable by the feed plunger under the normal working of the spring-pressed yieldable gas wall and the further incorporation in such feed control mechanism of means which will, upon any occurrence of abnormal pressure within the generator automatically act to lock the feeding mechanism in nonoperative position and thereby prevent any further generation of gas.

A further object of the invention is to provide an acetylene generator having a carbide dust screen removably interposed between a

primary gas outlet and a secondary distributing cavity which may be provided with one or more service outlets together with means of access thereto which permit the withdrawal of the screen, for cleaning or replacement purpose, and without any disarrangement of such service outlets.

Other objects and features of my invention, together with further detail concerning the objects already stated, will appear more fully from the following description and accompanying drawing in which—

Fig. 1 is a view in vertical central section, a portion of the water reservoir and a portion of the service structure being broken off, of an acetylene generator embodying my invention and showing the service connection as particularly adapted to the use of the generator as a flood light.

Fig. 2 is a partial view in vertical central section showing the fixed parts of the generator exactly the same as in Fig. 1 but with the working parts shown at a certain point of operating position.

Fig. 3 is a broken view in side elevation, at right angle to Fig. 1, showing the upper structure of the generator, with dotted detail of the crank portion of the control means, and also showing the upper service arrangement for adantation of the generator to use as a flood light.

Fig. 4 is a perspective view of the carbide dust screen sectionally shown in Fig. 1.

Fig. 5 is a full perspective view of the locking spring 32 portionally shown in Fig. 1 and Fig. 2.

Referring to the drawing, 1 is the upper portion of the water reservoir which also constitutes the gas generating chamber. The carbide container 2 is formed with an open top terminating in an outwardly extending flange 2a and with a lower neck portion 2b of reduced diameter which is flanged outwardly at its lowermost termination to form a contacting face for the rubber gasket 3. The gasket 3 is carried in a circumferential depression 1a of the water reservoir 1. The water reservoir is provided with ears 4 to which the swing bolts 5 are pivotally attached.

by the pins 6. Two semicircular bands formed with laterally extending arms 7 are clamped on to the carbide container neck 2b is spaced relation to each other by the 5 cross bolts 8, thus forming a yoke having open sides for the reception of the swing bolts 5. A gas tight joint between the water reservoir and the carbide container is effected by gasket compression upon screwing 10 down the wing nuts 9. The lowermost inwardly inclined bottom wall of the carbide container 2 is formed by a secondary funnel shaped piece 2c having a vertically extended mouth formation 2d which is threaded to 15 receive a correspondingly threaded portion of the valve member 10. The valve member 10 is provided with the lugs 10a which not only serve as finger opposition in its manipulation but also serve as interference means 20 through contact with the inwardly extending lip 1b of the water reservoir mouth and thus act to prevent the complete unscrewing of the valve member and thereby avoiding the serious consequence that would follow 25 its entire accidental displacement after the generator was charged and fully assembled. The yieldable gas wall, although composed of several separate parts, becomes when fully assembled a practically integral 30 working part of the generator and is designated as such in the drawing by arrow point and the numeral 11. Such single designation will simplify any functional description which may follow. The component parts of this 35 yieldable gas wall are, however, further described and designated in the drawing as follows: The rubber diaphragm 12 is provided with an enlarged bead portion 12a at its inner circular termination. A central 40 rigid spring supporting piece 13 is formed with an annular groove 13a in its lower side to receive the diaphragm bead portion 12a and a gas tight joint is effected through 45 compression therein by means of an underlying circular plate 14 and the headed bolt 15. The diaphragm 12 is preferably moulded to form 50 a circumferential recess, near its outer extremity, adapted to envelop the flange 2a of the carbide container 2 on three sides thereof as shown at 12b thereby affording double 55 assurance of a gas tight joint when this part of the diaphragm, together with the flange 2a, is compressed between the flattened section 60 16a of the generator cover 16 and the clamping ring 17 by means of the bolts and nuts 18 which are shown in Fig. 3. The generator cover 16 has an upwardly extending cylindrical housing portion 16b which, in conjunction with the cap 19, forms a complete 65 housing for the enclosed parts of the operating mechanism.

The full importance of such protection of working parts against weather elements and the entrance of grit such as sand or cinders, in a generator adapted to out of door use, will

be apparent after further description of my apparatus and it will then be seen that the particular design and arrangement of operating parts, to permit of their easy assembly under cover of such housing, constitutes an especially valuable feature of my invention as a whole.

The following description of parts of my generator which act in combination with the yieldable gas wall, heretofore described, to effect the automatic generation of gas in quantities commensurate with a variable service output will be comprehended more fully if it is first understood that such automatic action is brought about through 75 changes in balance of spring pressure upon the outside of the yieldable gas wall 11 as between the slightly varying gas pressure exerted against the inner side of said wall. It should be further understood that these 80 slight changes in gas pressure and the consequent changes in position of the gas wall, together with the feed plunger 20 suspended therefrom, are brought about by withdrawal 85 of gas from the generator for service use and the resultant feeding of carbide in quantity 90 only sufficient to supply gas for such service output and to cause the intermittent action 95 of the gas wall 11. While a spring pressure on the yieldable wall of about twenty pounds tensional force is required to establish a desired gas pressure of about two pounds within the generator, it is a fact that when this 100 balance of pressure becomes so established, the normal operative movement of the yieldable wall and its co-operating parts becomes extremely sensitive in action and any undue frictional interference in the working parts or of carbide therebetween will cause an 105 irregular feeding of carbide resulting in undesirable fluctuations of gas pressure. For this reason, the importance of the particular design of certain parts, together with their assembly arrangement, which I am 110 about to describe will become more apparent.

The feed plunger 20 is preferably loosely suspended from the yieldable gas wall 11 and in laterally swinging relation thereto, thus preventing any possible rigid frictional interference in its reciprocatory action 115 through the valve member feed opening 10b. Such suspension is effected by the cotter pin 21 in connection with a loosely fitting bearing 22a in the adjusting stud 22. The stud 22 is threaded into the head of the bolt 15 of the yieldable gas wall 11 thereby providing for the adjustability of the feed plunger 20 in exactly proper relation to the valve member feed opening 10b. A lock nut 23 is provided for rigidly securing the stud 22 in 120 place after the proper assembly relation is effected as described. The stem portion of the feed plunger 20 is preferably of tubular construction as shown and may be provided with the gas distributing ports 20a. A par- 125

ticular object of such tubular construction is to provide a more direct passage for the gas from the generating chamber of the water reservoir 1 to its point of action upon the yieldable gas wall 11. Instead of having to pass through the entire body of carbide, it will be seen that the newly generated gas, after passing through the valve member feed opening 10b, need only penetrate through the small body of carbide surrounding the feeding portion 20b of the feed plunger 20 before entering the lower open end 20c of the tubular stem portion of the feed plunger and that the gas may then pass freely therethrough and out of its upper open end 20d to act directly upon the gas wall 11. It will be understood, from previous reference to the sensitiveness of the yieldable gas wall to slight changes in pressure, that such direct action of the gas thereon results in a more ready response of the feed plunger action in shutting off the delivery of carbide after each intermittent discharge of same and thus reduces the range of undesirable fluctuations of gas pressure within the generator.

The carbide feeding portion 20b of the feed plunger 20 is of spiral formation and, for a generator particularly adaptable to flood light purpose as outlined herein is preferably formed by twisting rectangular metal stock and leaving an upper flat portion 20d for telescoping into the tubular plunger stem where it is secured by the rivet 20e. A lower flat portion (not shown) is also provided for mortising into the solid feed plunger tip 20f and is secured thereto by any suitable means. The upper termination 20g of the plunger tip is preferably of semiconical formation on both sides of the mortise therein. It will be understood that the stem and tip portions of the feed plunger are of cylindrical formation and of slightly less diameter than the valve member feed opening 10b to allow their free entrance therein. The greatest cross sectional dimension of the spiral formation 20b is somewhat less than the diameter of the valve member feed opening 10b, the purpose being to provide sufficient clearance between the spiral edges and the periphery of the feed opening to prevent the wedging of particles of carbide therebetween.

It will be understood that while I have expressed a preference for the use of rectangular stock for forming the spiral part of my feed plunger for the particular purpose cited in this application, other cross sectional forms may be used to particular advantage for different adaptation of the generator, such, for instance, as square stock in cases where only a limited delivery of carbide is required to supply a comparatively small gas output.

The spring supporting piece 13 is provided with a raised circular portion 13b for regis-

tration of the lower end of the pressure spring 24. The upper end of the pressure spring 24 is maintained under compression by the seating thereon of four downstanding prong portions 19a (only two of which appear in the drawing) of the cap 19. Further downstanding lips 19b of the prong portions 19a provide the means for central registration of the pressure spring 24. The cap 19 is secured in assembled position by means of screws 25—see Fig. 3—which pass through the housing 16b and are threaded into the prongs 19a. The crank 26 together with its handle portion 26a provided for manual control of generating operation is shown, partly in full and partly by dotted detail, in Fig. 3. The main shaft portions 26b and 26c are journaled in directly opposed sides and at the extreme top of the housing 16b. For convenience of assembly, such journaling is effected by providing the bearing perforations in the housing 16b with upper open sides so that the crank 26 may be dropped into place and be finally retained there by the cap 19 when the latter is in fixed position. A lug portion 26d of the crank 26 is shown in Fig. 3 as being in contact with a projecting portion 19c of the cap 19, such contact affording a stop against further counter clockwise revolution of the handle 26a, this being the position of the said handle when the crank 26 is in the position shown in Fig. 1. Upon a clockwise movement of the handle 26a to the extent of approximately one half revolution the opposite side of the same lug portion 26d contacts with the cap projecting portion 19c and prevents further movement of the handle 26a in that direction. The connecting rod carrier 27 is of U shape formation having openings 27a in both its arms adapted to a sliding fit on the connecting rod 28. It will be seen that such combination of the carrier and rod forms a complete bearing for the crank arm shaft 26d. The connecting rod 28 has an enlarged lower end portion 28a which is coupled in loosely swinging relation within an upstanding cup-shaped portion 13c of the pressure spring supporting piece 13 by means of the pin 29. The screw 30 is threaded into the upper end of the connecting rod 28, the head of said screw serving as a stop for the sliding carrier 27. The loosely coiled spring 31 is carried by the connecting rod 28, its tensional force being exerted between the lower enlarged portion 28a of said rod and the lowermost arm of the carrier 27 and thus serving to normally maintain the upper arm of said carrier in tensional contact with the head of the screw 30. The particular functional effect of such arrangement of the spring 31 will appear in the general explanation of generator operation to follow hereinafter. The locking spring 32 is fully shown in perspective in Fig. 5 and the description of its assembly

relation will be clear by reference to its portional numeral designations in this figure. It is held in place by positioning its coils 32a on the ends of the pin 29 with its free ends 32b resting on the pressure spring supporting piece 13 and with its loop portion 32c exerting tensional force against one side of the enlarged end portion 28a of the connecting rod 28. Such action of the spring 32 10 serves to convert the manual control mechanism to automatic safety locking means as will be more fully explained hereinafter.

A cavity 33 for receiving the screened gas before it passes to the service outlets therefrom is provided in my generator by means of the T 34 which is secured to the carbide container 2 by means of the nipple 35 and the lock nut 36. The outer opening of the T 34 is closed by a removable plug 37, access to 15 the cavity 33 being thereby afforded for the bodily removal—for cleaning or renewal purpose—of the carbide dust screen as fully assembled and shown in perspective in Fig. 4. The carbide dust screen is comprised of a body part 38 having a central gas passage 38a therethrough and with the cross inlets 38b communicating therewith. A disc of closely woven textile fabric 39 is crimped over a reduced section 38c of the body part 20 and the gathered circumferential margin of the fabric is bound tightly to the enlarged body portion 38d by means of a closely fitting ferrule 40. The yieldable packing ring 41 is backed by the shoulder body portion 38e. 25 A coiled spring 42 is secured to a reduced projection of the body 38 by means of the pin 43. The spring 42 is of sufficient length to insure, through its tensional compression by the plug 37, a dust proof contact between the packing ring 41 and the face of the nipple 35.

It will be seen that the displacement of the plug 37 permits the removal of the carbide dust screen as a whole, as heretofore described, and without in any way disturbing the service distribution outlets from the cavity 33, and which are shown and designated as the extension light gas cock 44 and the standpipe 45.

In the flood light adaptation of my generator as shown, the standpipe 45 is supported by the bracket 46 and is surmounted—see Fig. 3—with a swing joint 47, a needle valve 48 and a reflector 49. These parts, as also the burner provision, are not shown or described in detail as they may be of any design and arrangement common to apparatus of this character.

The operating parts of my generator are of such design and co-related simplicity that 60 quick and uniformly correct assembly is assured even when performed by unskilled labor. This is of particular economical importance in factory production and especially with a product having the commercial requirement of uniform operating efficiency.

The simple assembly of the carbide container, yieldable gas wall with feed plunger, connecting rod and locking spring attachment, and the cover with its open ended housing has already been made plain. The exact manner 70 and order of the assembly of the completely housed operating parts may be more clearly set forth as follows: The spring 31 is slipped over the connecting rod 28; the pressure spring 24 is dropped into its lower seat; the carrier 27 is placed on the crank-shaft 26d and the carrier arm openings 27a are then telescoped onto the connecting rod where they are retained by insertion of the screw 30. The ends of the crank main shaft are then 75 dropped into the open sided housing bearings and the positioning of the cap 19 puts the pressure spring under proper tension and completes the assembly.

The charging of the generator is accomplished by removing the carbide container from the water reservoir. The latter (not fully shown in the drawing) is charged with water to a certain indicated level, leaving a free space in its upper neck portion partially 90 shown as 1 in Fig. 1. The carbide container 2 is filled with carbide by inverting and the removal of the valve member 10 for that purpose. When thus charged and reassembled as in Fig. 1, the generator is ready for starting.

To start the generation of gas, the manually operable handle part 26a of the feed control means is swung in clock-wise direction and the entire carbide mechanism—including the yieldable gas wall 11, the feed plunger 20, the crank 26, the carrier 27 and the connecting rod 28—assumes immediately the approximate mean operating position shown in Fig. 2. In other words, it is in approximately this position of the operating mechanism 100 that the primary feeding of carbide takes place and that the balance of pressures, as between the spring pressure on top of the yieldable gas wall and the gas pressure on the under side of same, becomes established.

After this balance of pressures becomes so established, the feeding of carbide and consequent making of gas in limited quantity proportionate to the service requirement, 110 becomes entirely automatic. It should be particularly understood that my carbide feeding mechanism does not operate as a "charged" to deliver fixed and perhaps excessive amounts of carbide and which would require pronounced and extended strokes of the reciprocating plunger. While I have provided for a considerable possible length of the feed plunger stroke, it is by no means fully used in the actual carbide feeding action. The main purpose of such length of stroke is to 115 permit the yieldable gas wall to assume an approximate midway position of its complete flexible movement when the carbide feeding relation between the spiral feed section 20b of the plunger and the feed opening 10b is 120 125 130

established. When the yieldable gas wall 11 is in this approximate midway position, as shown in Fig. 2, the feed plunger is lowered so that its conical portion 20g is approximately in register with the periphery of the feed opening 10b. It will therefore be seen that only a slight further downward movement of the feed spiral 20b is required to permit a delivery of carbide and that only 10 a slight upward reaction of the feed plunger is necessary to stop the carbide delivery. This results in the establishment of an automatic gentle breathing action of the sensitively balanced yieldable gas wall with its co-operative feeding mechanism, such movement being accelerated by increase in withdrawal of service gas or being entirely stopped by the mere shutting off of the service output. Such resulting stoppage of automatic action 15 and further making of gas by shutting off all service output does not mean that the feed mechanism has assumed the locked position shown in Fig. 1 but simply that the feed plunger is held just high enough, by pressure 20 of gas shut within the generator against the gas wall, to prevent delivery of carbide. The carbide feeding action would be again automatically resumed upon renewed service withdrawal and without any manipulation what- 25 30 ever of the control handle 26a.

It will of course be understood that the generating of gas may be entirely stopped at any time by manually swinging the control handle 26a in counter-clockwise direction to 35 its approximate down-standing position, as shown in Fig. 3, thus leaving the operating mechanism locked in position shown in Fig. 1. It will also be obvious that no further gas can then be made—regardless of any attempted service withdrawal—until the control handle is manually swung in clockwise direction when the crank 26 is thrown off center and the pressure spring 24 thereby allowed to act. Upon such starting manipulation of the control handle, it immediately 40 assumes its approximate midway operating position where it works with a slight to and fro swing which is exactly indicative of the internal carbide feeding action. When the control handle travels the limit of its half circle swing and stands straight up—in direct opposition to its position shown in Fig. 3—it indicates that the carbide charge has become 45 exhausted.

It will become fully apparent, from the foregoing description of automatic operation, that the maintenance of a comparatively stable gas pressure within the generator is due to my provision of a carbide feeding mechanism that is highly sensitive in reciprocal response to slight changes in gas pressure and that such responsiveness has been attained by an arrangement of parts which practically precludes the possibility of abnormal or varying frictional interference. The spiral 50 plunger formation 20b and its working relation to the fixed feed opening 10b is an important part of this provision. In addition to its lateral freedom—due to the swinging suspension of the plunger stem—and consequent compensation against wedging of refractory particles of carbide between the spiral edges and the fixed periphery of the feed opening 10b, such wedging is further guarded against by the constant diagonal 55 change in operative contact relation between the spiral edges and said fixed periphery. Beyond these provisions against undue frictional interference, there remains the prime function of effecting a limited but ready delivery of carbide through a restricted feed opening together with means for the quick retardation of such delivery and it is in the accomplishment of this function that my spiral plunger formation becomes especially 60 important. It will be readily seen that, upon downward movement of the feed plunger, the general spiral contour acts both as a carrying and gentle forcing means to insure carbide delivery and at the same time presents a 65 certain amount of opposition to direct carbide gravitation, thereby tending to prevent over-feeding before the plunger reaction takes place. It will likewise be seen that with the first upward movement of the plunger, this 70 75 80 85 90 95 100 105 110 115 120 125 130

In generators to be used for illuminating purposes it is desirable to secure dehydration of the gas by having it pass through the carbide container on its way to the service outlet. Such desired practice results in the accumulation of a considerable amount of carbide dust in the lowermost portion of the carbide charge through a certain—although small—proportionate disintegration of the latter in taking up the moisture from the newly generated gas. This dust accumulation becomes most pronounced when a generator is operated continuously throughout the duration of its carbide charge and at approximately its full gas output rating. Such extreme operating conditions are not only common in generators adapted to flood light purpose such as I have illustrated but may almost be said to be the general rule. It has been found that various carbide feed plunger designs which work satisfactorily when the generator is not operated to fullest capacity of carbide charge and gas output, fail to give efficient service when subjected to the extreme conditions common to flood light operation, on account of becoming either partially or wholly clogged by lime accumulation caused by the carbide dust contacting with the condensation which takes place on the feed plunger surfaces that are intermittently ex-

posed to the steaming conditions within the generating chamber. It is in overcoming this fouling condition that the spiral plunger formation which I have provided becomes especially important. The explanation of its self cleaning function seems to lie largely in the scouring action of live carbide in passing over the continuously smooth spiral groove surface and the fact that the carbide passage opening although of constantly changing location, remains of never varying cross-sectional area at all positions of the reciprocating feed plunger.

It is in the consideration of this dust accumulating condition within the carbide container that another valuable feature of my tubular plunger stem provision becomes apparent. While it is a fact that more or less carbide dust is present in the normal charge of carbide, and especially so in granulated carbide such as is commonly used in the class of apparatus I have described, such dust does not become troublesome in generator operation until it accumulates in excessive proportion at or near the feed opening. For this reason, any further production of carbide dust through dehydration of the moist gas is of no particular consequences providing it is somewhat distributed throughout the carbide charge. It will be seen that the tubular plunger stem provides means for more ready and general distribution of the newly generated moist gas throughout the carbide container and it is to this end that the gas distributing ports 20a in the plunger stem may be provided.

By reference to the mean position of the working mechanism when the generator is in operation, as shown in Fig. 2, it will be seen that the feeding of carbide can not be forced by the manual swinging of the control handle 26a in further clock-wise direction. The only result of such movement would be the sliding down of the carrier 27 on the connecting rod 28 and the compression of the light connecting rod spring 31. As has been stated, the sole function of the spring 31 is to maintain the carrier 27 in contact relation with the head of the screw 30. The purpose of such maintenance of relation is to insure a relative movement of the control handle 26a during the intermittent carbide feeding operation. Such slight back and forth movement of the control handle affords visual evidence of the normal working of the internal generator mechanism.

Another result of the sliding relation of the carrier 27 on the connecting rod 28 is the total elimination of any possible strain on the control mechanism, or disarrangement thereof, resulting from the occurrence of any abnormal gas pressure within the generator. It will be seen by reference to the position of parts as shown in Fig. 1, that there is a small space between the cover for-

mation 16c and the outer portion 13d of the pressure spring supporting piece 13. The effect of any excessive gas pressure within the generator would be the abutting of these substantial parts and without any strain on the control mechanism—beyond the slight compression of the spring 31—as the connecting rod 28 would simply slide upward through the carrier arm bearings 27a.

After the foregoing description of general operation, the means employed for converting the control mechanism to positively acting safety locking purpose can be more clearly set forth. It has been explained that in normal operation the control parts are in approximately the position shown in Fig. 2. Sufficient excess gas pressure within the generator would result in moving the crank 26 to its extreme uppermost position and the locking spring 32 then acts, through the connecting rod medium, to throw the crank 26 past center and to thus positively lock the carbide feed plunger in the shut-off position as fully shown in Fig. 1. It may be observed that the sliding relation between the carrier 27 and the connecting rod 28 is an essential feature of my safety locking provision as, if the said carrier and rod were in fixed relation, the force of excessive gas pressure would be exerted against the crank 26 in its uppermost position and the locking spring 32 would be incapable of forcing the crank past center to the positively locked position shown. The fact that this safety locking means serves to prevent any resumption of carbide feeding until manually and intentionally released and also that its automatic action is positively assured regardless of the position of the generator, renders it an especially important adjunct of my invention.

Having now set forth the objects and nature of my invention and illustrative structures embodying the principles thereof, what I claim as new and useful and of my own invention, and desire to secure by Letters Patent, is:

1. In an acetylene generating apparatus comprising a carbide container having a restricted carbide delivery opening and provided with a yieldable gas wall, means for adjustably suspending a plunger from said gas wall, the said plunger having a carbide feeding portion operating through the said delivery opening, a cover backing for said gas wall having an upwardly extending portion forming closed side walls of an open ended housing, a cap piece forming a cover for said housing, the said cap piece having a portion projecting beyond the wall of said housing, a pressure spring resting upon said gas wall and maintained under tension thereon by the said cap piece, a shaft having a central crank formation operating within said housing, a handle connected with an end of said shaft exteriorly of said housing, the said han-

- idle being provided with a lug which in co-operation with the projecting portion of said cap piece limits the revolution of the said shaft, a carrier bearing for said crank formation, a connecting rod slidably connected with said carrier bearing and having its lower end pivotally connected with said yieldable gas wall, the said connecting rod being provided with a stop at its upper end to limit the movement 5 of said carrier bearing, a spring carried by said connecting rod for normally maintaining the said carrier bearing in contact with said stop and a spring supported by said gas wall and having tensional action against one 10 side of the said connecting rod.
2. In an acetylene generating apparatus comprising a carbide container having a restricted carbide delivery opening and provided with a yieldable gas wall, means for 15 adjustably suspending a plunger from said gas wall, the said plunger having a carbide feeding portion operating through the said delivery opening, a cover backing for said gas wall having an upwardly extending portion 20 forming closed side walls of an open ended housing, a cap piece forming a cover for said housing, a pressure spring resting upon said gas wall and maintained under tension thereon by said cap piece, a shaft having 25 a central crank formation operating within the said housing, a handle connected with an end of said shaft exteriorly of said housing, a carrier bearing for said crank formation and a connecting rod slidably connected with 30 said carrier bearing and having its lower end pivotally connected with the said yieldable gas wall.
3. In an acetylene generating apparatus comprising a carbide container provided with 35 a restricted carbide delivery opening and a yieldable gas wall, a plunger suspended from the said yieldable gas wall and provided with a spirally formed carbide feeding portion for operation through the said carbide delivery 40 opening, the said plunger being further provided with a hollow stem portion affording a gas passage from the upper termination of its spiral formation to a point adjacent to and below said gas wall, pressure means acting 45 upon said yieldable gas wall and manually operable means co-operating with the said gas wall and said pressure means for maintaining the spirally formed carbide feeding portion of said plunger entirely within the 50 said carbide container, said manually operable means controlling said co-operating means.
4. In an acetylene generating apparatus comprising a carbide container provided with 55 a restricted carbide delivery opening and a yieldable gas wall, a plunger having a spirally formed carbide feeding portion, means for 60 loosely suspending said plunger from the said yieldable gas wall in swinging relation there- 65 to to provide freedom of lateral movement of the said carbide feeding portion in its reciprocation through the said carbide delivery opening, pressure means acting upon said yieldable gas wall and manually operable means co-operating with said gas wall for 70 maintaining the spirally formed carbide feeding portion of said plunger entirely within the said carbide container, said manually operable means controlling said co-operating means. 75
5. In an acetylene generating apparatus comprising a carbide container provided with a restricted carbide delivery opening and a yieldable gas wall, a plunger having a hollow stem portion and provided with a spirally formed carbide feeding portion for operation through the said carbide delivery opening, means for loosely suspending said plunger from the said yieldable gas wall in swinging relation thereto, pressure means 80 acting upon said yieldable gas wall and manually operable means co-operating with the said gas wall for maintaining the spirally formed carbide feeding portion of said plunger entirely within the said carbide container, said manually operable means controlling said co-operating means. 85
6. In an acetylene generating apparatus comprising a carbide container provided with a restricted carbide delivery opening and a yieldable gas wall, a plunger having a hollow stem portion and provided with a spirally formed carbide feeding portion for cooperation with the carbide delivery opening and means for moving the plunger axially whereby to cause a reciprocating motion of the spirally formed feeding portion at the carbide delivery opening. 90
7. In an acetylene generating apparatus comprising a carbide container provided with a restricted carbide delivery opening and a yieldable gas wall, a plunger having a hollow stem portion and provided with a spirally formed carbide feeding portion extending through the carbide delivery opening and cooperating with said opening to feed carbide therethrough and means for yieldingly suspending the plunger to permit reciprocating axial movement of the spirally formed carbide feeding portion of the plunger whereby to feed carbide through the delivery opening. 105
- In testimony whereof I have signed this specification this 3rd day of October, 1929.
